UNITED STATES PATENT OFFICE.

EVERETT B. CUSHMAN, OF SAN JOSE, CALIFORNIA, ASSIGNOR, BY MESNE ASSIGNMENTS, TO O. D. COLLIS, OF CLINTON, IOWA.

WATER COOLER.

Application filed June 3, 1922. Serial No. 565,764.

To all whom it may concern:

Be it known that I, EVERETT B. CUSHMAN, a citizen of the United States, residing at San Jose, in the county of Santa Clara and 5 State of California, have invented certain new and useful Improvements in Water Coolers, of which the following is a specification.

My invention relates to water-coolers especially adapted for gasoline engines; and particularly to that type of such coolers in which a stationary radiator is positioned within the space circumscribed by an offset rim of the engine fly-wheel and is exposed 15 to a current of air created by the rotation of the fly-wheel.

My invention consists in the novel water-cooler which I shall hereinafter fully describe. Its objects and distinguishing characteristics will be better understood by an exposition of the same to follow the description of the device, in connection with the accompanying drawings, in which—

Fig. 1 is a central vertical section of my 25 water-cooler.

Fig. 2 is a part sectional front elevation of the same.

In the drawings, the reference numeral 1 designates an open-sided fly wheel, which 30 is mounted upon a rotary shaft 2 extending from the frame 3 of the engine. Said fly wheel has an off-set rim 4, and inclined spokes 5, which act as the blades of a fan to set up a current of air through the fly- 35 wheel from side to side.

Within the off-set portion of the rim 4 is a stationary radiator 6, preferably substantially annular in form. Said radiator may be constructed in any well known manner, and is shown in the drawings as of the 40 barrel or cylinder type, having transverse air passages 7, through which the air is caused to pass by the revolving fan-shaped spokes 5 of the fly-wheel, and water passages 8 formed between the walls of said air passages. The periphery of the radiator 6 lies in close proximity to the interior of the fly wheel rim 4, and is preferably provided with a ring 9 of felt or other suitable packing material, to prevent any substantial amount of air from being drawn 45 between the periphery of the radiator and the rim of said fly wheel.

The radiator 6 is positioned about and supported by an approximately central mem-

ber 10, which is mounted upon the engine frame 3, as shown in Fig. 1. This supporting member 10 has within it the casing 11 of a water circulating pump, which may be of any suitable form, but is here shown as a centrifugal pump having an impeller 12 driven by gears 13 from the hub of the fly wheel 1. The water is drawn into the pump through an inlet connection 14, which opens into the casing 11 in its central region, 65 and is discharged at 15 into the radiator, the peripheral region of said casing being open directly to the radiator tubes at its upper and left hand sides as viewed in Fig. 2. A partition or baffle plate 16, Fig. 70 2, extending from the pump casing 11 to the outer periphery of the radiator, causes the water to pass through said radiator in an approximately circular path until it reaches the outlet connection 17, thus 75 traversing the entire radiator.

The impeller 12 of the circulating pump is mounted upon, or preferably formed integrally with a spindle 18, Fig. 1, which is journaled in the casing 11. A thrust ball 80 19, backed by a spring 20, is mounted in the rear end of said spindle 18, and acts to keep a thrust shoulder of the impeller in close relation to the front wall of the casing, as shown at 21, to prevent leakage 85 of water through the outer spindle bearing. Lubrication of said bearing is provided for by a tube 22 extending through the radiator to an accessible position at its rear.

From experience with and tests on the 90 various types of radiators, whether stationary or rotary, commonly used in connection with a fly-wheel for circulating air and forming a protecting housing for the radiator, I have found that they are low in efficiency, due to the air having to turn sharp angles, either in entering or passing out, since in all forms of which I am aware, the fly wheel is so constructed as to sharply turn the air angularly from a solid face or 95 radially outwardly through its rim.

In my invention, however, as hereinbefore set forth, the entire flow of air passes through both the radiator and fly wheel from side to side, while at the same time, 105 the fly wheel houses and protects the radiator, said wheel thus being a fly wheel, a fan, a hood for directing the air and a radiator guard all formed in one.

Another difficulty in common practise is 110

that of obtaining sufficient areas for the air to produce the maximum efficiency in a given space. The construction of the barrel or cylinder type of radiator, either stationary or rotary, is of such a nature as to limit itself to certain fixed air openings unless the size of the entire unit be materially increased. For instance, a cylinder or barrel type radiator must have sufficient areas at the ends of the cylinder to supply air to the entire inside face of the radiator.

This means that where fly-wheel clearance is limited in diameter, it cannot be used, as the increase in length or width of the wheel after having reached a certain ratio between the end areas and the face areas, will not increase its capacity.

In my invention, either the diameter or width may be altered without affecting the other dimension. If the clearance is such that it will permit the use of only a very narrow unit, the diameter may be increased and the width decreased without affecting the cooling capacity.

On the other hand, if clearance will not permit of a large diameter, it may be reduced and its length increased without affecting the cooling. For compact construction, and for obviating fittings and joints, the water circulating pump is best placed within the radiator. The member 10 which forms the support for the radiator also forms the housing for the pump. This member also serves to direct the flow of water evenly through the entire radiator. As water enters at 14 it is taken into the center of the pump and is thrown by the pump impeller out into the radiator on the upper and left hand side of the pump which is open to the radiator. In order to pass out from the radiator at 17 it will travel with even distribution through the entire radiator around the center member 10.

In many of the uses of gasoline engines, especially for portable work, efficiency is mainly dependent on minimum weight and space. Radiator cooled engines are, therefore, desirable. But radiators are fragile, and in portable work are easily injured or ruined. They also require a fan for cooling and the ordinary fans require chains or belts for driving. These slip or clog when exposed to spray materials in orchard or crop spraying, or to paints in modern machine painting or to concrete or other dust in many kinds of work. The difficulties of mount-

ing and protecting a radiator have resulted in the protective association of the radiator with the fly-wheel, and the latter by being constructed to serve as a fan, dispenses with the ordinary fan, and its driving belt or chain, and moreover economizes space. This advance in the art has, however, been attendant with the requirement of radiators both unnecessarily large and expensive, due chiefly to an inadequate supply of air resulting from drawing the air in and then discharging it from the same side of the fly-wheel, or from one side and out through the periphery of the wheel. Such course of the air flow results in excessive friction from the sharp changes of direction, and hence reduces velocity, which in turn requires increases in size and cost of the radiator and fly-wheel. In contrast to this, my invention, by taking the air from either side of the fly-wheel and passing it through the radiator and discharging it on the opposite side of the wheel, eliminates the expense of a separate fan, its mounting, and its driving means, with no extra space consumed for the radiator. Moreover, the radiator is fully protected from injury, without the expense of otherwise protecting or mounting it.

I claim:

1. A water-cooling means comprising a stationary radiator; a rotatable fly-wheel within which the radiator lies; and means carried by the fly-wheel for creating a current of air through both radiator and fly-wheel from side to side.

2. A water-cooling means, comprising a stationary radiator; and a rotatable, open-sided fly-wheel within which the radiator lies, said fly-wheel having spaced, fan-shaped spokes operating in association with one face of the radiator to create a current of air through the radiator and fly-wheel from side to side.

3. A water-cooling means comprising a rotatable, open sided fly-wheel having an offset rim, and spaced, fan-shaped spokes; and a stationary radiator lying within the space circumscribed by the offset rim of the fly-wheel, with its inner face exposed to the operation of the fan shaped spokes of the fly-wheel whereby a current of air is created through the radiator and fly-wheel from side to side.

In testimony whereof I have signed my name to this specification.

EVERETT B. CUSHMAN.
